UNITED STATES PATENT OFFICE.

ELWIN S. ANDERSON, OF CANASTOTA, NEW YORK.

BOW-FACING OAR.

SPECIFICATION forming part of Letters Patent No. 727,731, dated May 12, 1903.

Application filed February 19, 1903. Serial No. 144,102. (No model.)

To all whom it may concern:

Be it known that I, ELWIN S. ANDERSON, a citizen of the United States, residing at Canastota, in the county of Madison and State of New York, have invented certain new and useful Improvements in Bow-Facing Oars; and I do declare the following to be a full, clear, and exact description of the invention, such as will enable others skilled in the art to which it appertains to make and use the same.

This invention relates to improvements in bow-facing oars.

The object is to provide a construction whereby an oarsman may sit facing the bow of the boat while rowing in the usual way to propel the boat forward and whereby the oar may be readily manipulated to move the blade into and out of the water and as readily applied to and removed from the fixed part of the oar-lock.

With these and other objects in view the invention consists of certain novel features of construction, combination, and arrangement of parts, as will be hereinafter more fully described, and particularly pointed out in the appended claim.

In the drawings, Figure 1 is a top plan view showing only so much of the oar and side of a boat as is necessary to illustrate the invention. Fig. 2 is a cross-section through the side of the boat, showing the invention in end elevation. Fig. 3 is an inner side view. Figs. 4 and 5 are sections taken, respectively, on the lines 4 4 and 5 5 of Fig. 1. Fig. 6 is a detail view of one of the oar-sections and its gear.

Referring now more particularly to the drawings, the numerals 1 and 2 represent, respectively, the handle and blade sections of an oar, which are provided at their meeting ends with gear-segments 3 and 4, meshing with each other and adapted to transmit motion from the said handle-section to the said blade-section. Each of these segments is provided with a pair of parallel plates 5, which fit within recesses formed in opposite sides of the coacting oar-section and are secured thereto by bolts 6. The gears are inclosed within a casing open at each end and consisting of top and bottom plates 7 and 8, connected by side pieces 9, and the oar-sections 1 and 2 are pivoted to said casing by means

of bolts 10, so that when movement is imparted to the section 1 the latter will transmit a swinging movement to the section 2 through the instrumentality of the two gears 3 and 4. By this construction it is obvious that when the oar is suitably mounted upon a boat the oarsman can sit facing the bow and by operating the handle-section 1 transmit reverse swinging motion to the section 2 to propel the boat forward.

The bottom plate of the casing is provided with depending ears 11, through which passes a bolt or shaft 12, mounted upon a yoke 13, which is provided with a stem 14. The casing is adapted to pivot on this shaft or bolt to adapt the latter to be raised and depressed in the operation of rowing to move the blade into and out of the water.

The yoke 13 has a flat base-plate which fits within a correspondingly-shaped channeled socket 15 upon the top of a bracket 16, secured by bolts 17 to the side 18 of the boat or a plate or board attached thereto. Through the socket extends an opening 18, which is in line with an opening in a lateral ear 19 at the lower end of the bracket. The stem 14 fits within these openings and secures the yoke to the bracket in such manner as to allow the oar to be readily applied to and removed from said bracket, and the oars also will swing to rest on stern of the boat. The yoke fits snugly within the channeled socket and is held by the stem 14 against longitudinal movement and by the side flanges of the socket against lateral movement, thus preventing the yoke from having any independent play when the oar is manipulated.

From the foregoing description, taken in connection with the accompanying drawings, the construction and operation of the invention will be readily understood without requiring a more extended explanation.

Various changes in the form, proportion, and the minor details of construction may be resorted to without departing from the principle or sacrificing any of the advantages of this invention.

Having thus described my invention, what I claim, and desire to secure by Letters Patent, is—

In a bow-facing oar, the combination of a

bracket provided with an apertured lug at its lower end and at its upper end with a channeled socket having an opening in line with the opening in the lug, a yoke fitted in said 5 socket and provided with a stem projecting down through the opening and lug, a shaft or thole-pin carried by the yoke, a casing pivotally mounted on said shaft or pin, and an oar consisting of sections pivotally connected

to the casing and provided with intermeshing 10 gears, substantially as described.

In testimony whereof I have hereunto set my hand in presence of two subscribing witnesses.

ELWIN S. ANDERSON.
